SHEARS OR THE LIKE

Samuel Briskman, New York, N. Y.

Application May 3, 1957, Serial No. 46,011

Term of patent 14 years

(Cl. D22—5)

Fig. 1 is a side perspective view of shears showing my new design as they appear with the blades in partly opened position;

Fig. 2 is a side elevational view thereof showing the blades in closed position;

Fig. 3 is a top edge view thereof;

Fig. 4 is a bottom edge view;

Fig. 5 is an end elevational view looking from the left of Fig. 2; and

Fig. 6 is an enlarged cross sectional view taken through the blades on the line 6—6 of Fig. 1.

This application is a continuation-in-part of my prior application, Serial No. D. 43,219, filed October 3, 1956.

The essential features of my design reside in the portions shown in solid lines on the drawing, characterized particularly by the provision of a beveled edge on each of the blades adjacent the cutting edge thereof and with

inturned edge portions thereon scalloped in complementary relation, forming the cutting edges, substantially as shown.

I claim:

The ornamental design for shears or the like, as shown and described.
